UNITED STATES PATENT OFFICE.

ARTHUR APPLEYARD, OF BEAVERDALE, PENNSYLVANIA, ASSIGNOR OF ONE-HALF TO
WILLIAM J. FAUX, OF PHILADELPHIA, PENNSYLVANIA.

HOIST FOR COAL-MINES.

1,246,517.

Specification of Letters Patent. Patented Nov. 13, 1917.

Application filed March 7, 1917. Serial No. 153,035.

To all whom it may concern:

Be it known that I, ARTHUR APPLEYARD, a citizen of the United States, and a resident of Beaverdale, county of Cambria, State of 5 Pennsylvania, have invented certain Improvements in Hoists for Coal-Mines, of which the following is a specification.

My invention relates to certain improvements in the means for handling miner's 10 cars in coal and other mines.

One object of the invention is to avoid the expense incident to removing rock other than coal in order to render the galleries of 15 sufficient depth to admit of the movement of mules or electric locomotives.

Another object of the invention is to design the mechanism so that it can be worked in galleries in which the seams of coal are very narrow.

20 Still another object of the invention is to operate the cars independently in the several galleries and to provide electric mechanism by which the hoist can be actuated at any point in the gallery.

25 In the accompanying drawings:

Figure 1 is a perspective view showing one of the mine galleries partly broken away and illustrating my invention;

Fig. 2 is a plan view showing the two galleries and the independent mechanism for each gallery; and

Fig. 3 is a side view of my improved hoisting mechanism.

This invention relates particularly to the 35 mechanism for handling the cars in coal mines and mines having comparatively narrow veins. It has been the general practice to cut the coal in the veins in order to increase the depth of the gallery and to cut 40 away the stone to a sufficient depth to allow for the passage of the mules or an electric car into the working gallery from the main gallery. This extra cutting is waste and is exceedingly expensive as the stone is harder 45 than the vein of coal and must be loaded on cars and removed to the surface.

By my invention, I am enabled to reduce the height of a working gallery and in many instances not cutting beyond the depth of 50 the vein of coal, the height being sufficient to allow a man to work and the ordinary type of car to be drawn into and out of the working gallery.

A is the main gallery and B, B' are two 55 of the series of working galleries and the

length of these galleries depends considerably upon the vein of coal and the width will vary under ordinary conditions. There are usually comparatively large pillars C at the main gallery between each working gallery, as shown.

1 is the main track extending through the main gallery and leading to tracks connected to the surface or with elevators, according to the type of mine. 2, 2 are the temporary 60 tracks extending into the working galleries B, B'. 3 are the switches for driving the car from the main track onto the working tracks 2. 4 is the car adapted to the tracks 1 and 2, and this car is loaded by a miner in the 65 working gallery and when it passes onto the main track 1 it is drawn out by mules or a locomotive, as it will be understood that the main gallery is of a greater height than the working gallery in the majority of cases. 70 The floor of the working gallery is usually inclined, the grade being such that when the car in the working gallery is released it will travel by gravity out of the gallery and onto the main track. The great difficulty has been to provide means for taking the car into the farther end of the gallery where the work is being done.

At one side of the track 2 in each gallery is a hoisting apparatus 5 consisting of a 75 drum 6 mounted in suitable bearings 7 and an electric motor 8 geared to the drum through gearing 9 and 10. Mounted on the drum is a rope 11 in the present instance extending around a guide wheel 12 and around a pulley 13 at the extreme end of the gallery. The pulley 13 is mounted on a strut 14 secured to the floor and ceiling in the ordinary manner and the wheel 12 is also carried by a strut 15. At the end of the rope 11 80 is a hook 16, which engages a pin 17 on the car 4 so that when the hook is in engagement with the pin and the motor is driven in one direction the drum will coil the rope and drag the car to the point desired.

100 In order to enable a miner to handle the car properly without having to go to the hoisting mechanism, I provide an electric switch 18 connected by wires to the motor 8 in the ordinary manner so that on operating this switch the miner can cause the car to traverse the track to any point desired. This switch is mounted on a post 19 held in position in any suitable manner, or it can be mounted on a temporary post and shifted 105 110

from place to place. The wires, however, are preferably arranged overhead so that the operator will not come in contact with them.

5 In order to prevent the racing of the drum, when the rope is slack, I provide an automatic brake 20 pivoted at 21 to a strut 22 and this brake has a shoe 23 which bears against the drum and has, at its outer end, 10 a grooved wheel 24, which rests on the rope so that the moment the rope becomes slack the brake will come in contact with the drum 6, but, as soon as the rope is taut again, it will raise the brake lever 20 and 15 its shoe 23 clear of the drum. The hoisting mechanism is temporarily held in position by jack pipes 25 which extend to the roof. I have shown three jack pipes, but it will be understood that any number can be used, 20 as desired.

The operation is as follows:

When the working galleries are started, the opening is made and the temporary track partly laid and connected to the main track. 25 After the working has been made to a certain depth, then the hoisting mechanism is located in position at one side of the track, as shown, and at the entrance of the working gallery. A strut is placed at 30 the extreme inner end of the work and the rope is passed around the pulleys, as shown, so that when a car is brought to the entrance of a working gallery, it is coupled to the rope, and by operating the switch mechanism the drum is set in motion and the car is hauled up the slight incline and into the gallery to the point where the miner is working. It is held in this position until 35 it is filled, then the drum is released and 40 the car returns by gravity to the entrance of the working, and the driver in the main gallery will uncouple the rope allowing the car to pass onto the track in the main gallery. The empty car will be brought into 45 position and coupled to the rope. The miner will again operate the switch and the empty car will be drawn up into position in the working gallery. Some of these galleries are comparatively long and considerable 50 time is usually wasted by the miner going the full length of the gallery to operate his car. Whereas, by my improvement, the miner can devote his entire time to mining coal and loading the cars.

55 By this arrangement, each gallery is in-

dependent of the others, so that one miner does not have to wait upon others for power mechanism for handling his cars and the use of mules and expensive electric locomotives are entirely dispensed with in the 60 working galleries.

While I have described the hoisting apparatus located at the entrance of the working gallery, in some instances, it may be located some distance back of the entrance 65 without departing from the essential features of the invention, and as the working is increased in depth the hoisting apparatus may be moved into the working gallery so as to avoid the use of unnecessarily long 70 hoisting ropes.

I claim:

1. The combination of a mine having a main gallery and a series of working galleries; a track in the main gallery; a series 75 of tracks in the working galleries and connected to the main track; cars adapted to travel on said main track and to be shifted onto any one of the tracks in the galleries; a hoisting apparatus located in a fixed position at the entrance to each working gallery, the floor of each gallery being arranged on an incline from the entrance to the point where the coal is mined, the hoisting apparatus being arranged to draw the empty 80 car into the gallery to the point where the miner is working, the full car being allowed to run by gravity in position to be transferred to the main track.

2. The combination of a mine having a 85 main gallery and a series of working galleries; a track in the main gallery and a track in each working gallery connected to the main track, the said tracks in the working galleries being arranged on an incline 90 upward from their connection with the main gallery; a hoisting apparatus located at the entrance of each working gallery and having a rope extending to the inner end 95 of its gallery and around a pulley and arranged to be coupled to a car so that the empty car can be drawn into the gallery by the hoisting mechanism, the loaded car being allowed to return by gravity; and an electric switch at the miner's station connected 100 to the hoisting apparatus so that the operator can control the motor without leaving his station.

In witness whereof I affix my signature.

ARTHUR APPLEYARD.
